UNITED STATES PATENT OFFICE

JOSEPH M. BRILL, OF CLEVELAND, OHIO, ASSIGNOR, BY MESNE ASSIGNMENTS, TO CONSOLIDATED CONNECTOR PATENT CORPORATION, OF WILMINGTON, DELAWARE

SUPPORT FOR AN AUTOMATIC CONNECTER

Application filed February 27, 1929. Serial No. 343,093.

This invention relates to automatic train pipe connectors and particularly to a connector wherein the head is yieldingly supported by a bracket which depends from a car coupler. It has been the practice to support the head in proper position for coupling by means of a rigid member which extends diagonally between the head and bracket, and which is pivotally connected at one end to the head and is slidably mounted at the other end in the bracket. The bracket end is threaded and is provided with adjusting nuts for enabling the head to be adjusted to the proper position.

Usually, the rigid member which holds the head in coupling position comprises a rod which passes through an aperture in the bracket. During the normal coupling operation, there is a slight upward movement of the heads with relation to the bracket, and during such movement the rod is free to slide through the aperture. If for any reason, there should be a downward or lateral movement of the connector heads during the coupling operation, then the rod tends to bind against the walls of the aperture, and if the strain is sufficiently great, the rod will bend and will thereafter fail to maintain the head in proper coupling position. Such downward or lateral movement of the head is particularly apt to occur if for any reason the connectors should fail to couple. Such movements are also apt to occur if the connector should strike a butting block at the end of a track with considerable force. The tendency of the rod to bind in the aperture is due to the fact that the head moves about one point as a center while the rod passes through the bracket at a different point, and that the rod is threaded on the portion which extends through the bracket. Such threads tend to bind against the bracket unless the head is disposed in the normal central position.

The principal object of the present invention is to provide means for holding the threaded portion of the rod out of contact with the bracket, while the head is being supported in coupled position. In this way, the rod is free to move backwardly irrespec-

tive of the position of the head. A further object is to provide head supporting means which can be readily incorporated in existing connectors in a simple and expeditious manner.

Referring now to the drawing, Fig. 1 shows a side elevation of an automatic trainpipe connector embodying my invention; Fig. 2 is an enlarged horizontal section through the supporting bracket, showing the position of the rod when the head is uncoupled; Fig. 3 is a vertical section taken through the connection between the rod and bracket taken on the line 3—3 in Fig. 2, Fig. 4 is a diagrammatic view showing the effect of a downward movement of the head with reference to the bracket, and Fig. 5 is a plan view of a part of the head adjacent the connection between the head and supporting rod;

Fig. 6 is a horizontal section through the supporting bracket, showing a plan view of the pivot block and seat; and Fig. 7 is a section taken on lines 7—7 in Fig. 6.

In the drawing there is shown a car coupler 10 from which depends a supporting bracket 11. The bracket is secured to the underside of the coupler, by any suitable means, such as bolts 12, and is arranged to extend downwardly and rearwardly. The lower end of the bracket is shown as having spaced arms 30, formed with aligned slots 31, which open at the front side of said arms. A pivot block 32 has trunnions 33 fitted in said slot, so that the block is supported for rocking movement about a horizontal axis. The ends of the trunnions 33 are provided with flanges 34, which bear against the outside surfaces of the arms 30, thereby preventing movement of the block transversely of the arms. The block is also formed with an aperture 35, which is adapted to receive the shank 15 of the connector head 13. The front face of the pivot block above and below the aperture 35 is formed with substantially cylindrical bearing surfaces 37. A spring seat 38 is arranged in front of the pivot block and is formed with an aperture 39 for receiving the shank 15. A spring 41 is interposed between the seat 38 and the head 13 and acts to force the head away from the supporting

bracket. The rearward face of the seat is provided with two lugs 40, which have substantially semi-cylindrical surfaces adapted to be seated in the bearing surfaces 37 of the 5 pivot block. It will be observed that the engagement of the lugs 40, with the pivot block, provides a pivotal connection between these parts which permits rocking movement about an axis perpendicular to the axis of the 10 pivot block. A positioning of the shank when moved with relation to the block is shown by the broken lines 41 in Fig. 6. A member 16 extends between the head and the bracket above the shank and functions to 15 support the head in proper position for coupling purposes.

The member 16 is shown as a rod, the forward end of which is pivotally connected at 17 to the head, and the rearward end of 20 which passes through an aperture 18 in a transverse wall 19 of the supporting bracket. The rod has considerable clearance in the aperture, as is illustrated in Figs. 2 and 3, and is slidably mounted therein. The rear- 25 ward end of the rod is threaded, as at 20, and is provided with an adjusting nut 21, and a lock nut 22, for enabling proper adjustment of the head to be made with relation to the car coupler.

30 To center the rod in the bracket aperture, I have shown the wall 19 of the bracket as having a convex portion 25 around the aperture, and I have shown the nut 21, as having a concave surface 26 which coacts with the 35 convex part of the bracket. These coacting surfaces center the rod automatically in the aperture, as the head is moving forwardly during the uncoupling operation. I have found that the convex and concave portions 40 may be either frusto-conical in shape or hemispherical in shape. The concave face of the coacting nut 21 is preferably flatter than the coacting convex part of the bracket, as is shown in Figs. 2, 3 and 4. By making 45 the nut sufficiently wide to bring the uppermost edge thereof above the top wall of the aperture when the rod is resting on the bottom of the aperture, the rod is always centered during the forward movement of the 50 head.

55 While I have shown and explained the concave portion of the nut, as being different from the convex part of the cooperating bracket, it is evident that the centering of the supporting rod can be effected if the convex and concave portions are complementary to each other. An advantage, which I have found however, in making such portions slightly different in shape is that the rod 60 will be maintained out of contact with the wall more readily if the head is moved downwardly while under the action of the spring 14. This is best illustrated by the diagram in Fig. 4, which shows the normal position 65 of the nut in full lines. The broken lines

21a indicate the position of the nut when the head is moved downwardly. It is apparent that such downward action will cause a pivotal action between the nut and bracket adjacent the top of the wall, and that such contact will lift the rod away from the bottom of the aperture, and thus prevent a binding action if the head should be moved rearwardly while in such downward position. The same result is obvious if the head should be moved laterally and rearwardly while under the action of spring 14.

70 Upon coupling, there will be a slight movement of the head rearwardly toward the bracket before the rod will be free to drop into engagement with the bracket wall. The extent of such movement depends upon the overlapping area between the bracket wall and the adjusting nut. Such area is 75 sufficient in amount to protect the threads on the rod immediately forward of the adjusting nut, thus allowing sufficient adjustment to be made at a subsequent period to satisfy all practical requirements.

80 A further advantage of my invention is the fact that the rod cannot bind against the bracket, if for any reason the connector head fails to couple, and if for any reason the connector head is moved either downwardly or laterally in a sudden manner. My invention thus increases the flexibility of the connector and accomplishes this result in a 85 simple and satisfactory way.

90 I claim:

95 In an automatic train pipe connector having a connector head which is mounted for universal movement with reference to a supporting bracket, means for supporting said head in normal position for coupling, and comprising a rod pivoted to the head and 100 passing through an opening in the supporting bracket, said opening being substantially 105 larger than said rod and being surrounded by a rearwardly extending boss, and means to secure said rod in said bracket comprising a nut having a concave surface which is dissimilar from that of the boss and which is adapted to engage the edge of the boss in 110 substantial line contact.

115 In testimony whereof, I hereunto affix my signature.

JOSEPH M. BRILL.
